ATTORNEY

UNITED STATES PATENT OFFICE.

GEORGE W. SLEEPER, OF WESTBOROUGH, MASSACHUSETTS, ASSIGNOR OF
ONE-HALF TO WILLIAM A. REED, OF SAME PLACE.

SHOE.

SPECIFICATION forming part of Letters Patent No. 320,406, dated June 16, 1885.

Application filed October 11, 1884. (No model.)

To all whom it may concern:

Be it known that I, GEORGE W. SLEEPER, of Westborough, in the county of Worcester and State of Massachusetts, have invented a new and useful Improvement in Manufacture of Shoes; and I do hereby declare that the following is a full, clear, and exact description of the same.

My invention relates to the form of shoe-
upper shown in United States Letters Patent
granted me on the 25th day of March, 1884,
and in United States Letters Patent granted
W. A. Reed, August 19, 1884. In these pat-
ents the split was represented as made from
rear to front in the upper blank or leather,
ending at the point of termination of the slit
or opening of the front of the shoe, the split
extending all the way across the leather up
to that point. This mode of splitting left a
flap on each side connected to the blank or
upper on the line of the split termination,
which flaps were removed as waste material.
The leather in front of the line of termina-
tion of the split remained of the ordinary or full
thickness of the leather, while that in rear
was split.

My present invention consists of an upper
formed out of a blank split from the heel or
rear forward, on lines substantially conforming
to the shape of the upper, as contemplated,
whereby the sides in those parts from which
the flaps were removed in my previous patent
are left of full thickness.

In the accompanying drawings, Figure 1 repre-
sents in plan the upper split according to my
improved method, one side being turned up.
Fig. 2 represents an upper which is split
through only a portion of the width of the
leather, leaving the edges of full thickness.

In the drawings the leather or blank is repre-
sented as cut in shape the same as that
shown in my said patent. It is split from the
rear forward, preferably on an incline, as
shown in the patent to Reed aforesaid, and
the split extends from side to side, as shown

in Fig. 1, or through only a portion of the
width, as shown in Fig. 2, until it reaches the
points $x' x'$, when the knife or knives are
turned out of the leather or aside and caused
to cut on the lines $x' y'$ as far as the point y' .
The split portion of the leather from the line
 $x' x'$ forward is wholly contained between the
lines $x' y'$, and terminates at the point y' , and
only the counters and upper parts of the shoe
are of split leather. This leaves the parts
marked B B, bounded by the lines $x' y' z$,
heretofore split, of full thickness, and the
lines $x' y'$ are substantially those given the
front part of the upper, where the lacing is
applied. The approximately triangular parts
 $x' y' z$ on each side are parts which require
strength, and the full thickness here obtained
by this improved mode of splitting is desirable
in the manufacture of shoes.

From this description it will be understood
that no part of the leather is wasted, the higher
parts of the upper along the shoe opening in
front, and the counter or upper part of the
counter being of split leather and composed on
one side of the upper and on the other of the
lower half of the blank leather. A machine
for splitting these upper-blanks is shown in
an application filed by me in the United States
Patent Office, of even date herewith; but I
do not herein limit myself to any special ma-
chine or mode of operation.

What I claim is—

A shoe-upper having the front and side
portions, B, of full thickness and the counter
or upper part thereof formed out of the upper
and under split portions of the blank, sub-
stantially as described.

In testimony whereof I have signed my
name to this specification in the presence of
two subscribing witnesses.

GEORGE W. SLEEPER.
